(57) **CLAIM**

The ornamental design for tweezers, as shown and described.

DESCRIPTION

FIG. 1 is a perspective view of tweezers showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the tweezers where the tweezers are attached to a connecting bar; and,

FIG. 10 is a perspective view of the tweezers where the tweezers are separated from the connecting bar.

The broken lines in FIGS. 9 and 10 showing the connecting bar depict environment and form no part of the claimed design. The other broken lines in the drawings depict portions of the tweezers that form no part of the claimed design.
